UNITED STATES PATENT OFFICE.

CARL N. MOLLER, OF NEW YORK, N. Y.

PHONOGRAPH-REPRODUCER

1,296,833.

Specification of Letters Patent. Patented Mar. 11, 1919.

Application filed October 7, 1916. Serial No. 124,245.

To all whom it may concern:

Be it known that I, CARL N. MOLLER, a citizen of the United States, residing in the city of New York, borough of Manhattan, 5 county and State of New York, have invented a certain new and useful Phonograph-Reproducer, of which the following is a specification.

This invention is a phonograph reproducer, and the object of the invention is to amplify the vibrations of the stylus bar in their transmission to the diaphragm. A further object of the invention is to provide a phonograph reproducer adapted to operate 15 on records either of the hill and dale or lateral cut type.

Speaking generally, the salient feature of the invention consists in an amplifier coöperating with the diaphragm and stylus bar, 20 whereby the movements of the stylus bar are materially amplified prior to their transmission to the diaphragm, thereby increasing the degree of vibration of said diaphragm.

From a more specific standpoint, the invention may be said to consist in an amplifying connection intermediate the diaphragm operating end of the stylus bar and the diaphragm, whereby a relatively short 25 travel of said end of the stylus bar is translated into a relatively greater movement of the diaphragm. In other words, the present invention embodies means, positioned intermediate the diaphragm operating end of the 30 stylus bar and the diaphragm, whereby the vibrations received at said end of the stylus bar are transmitted to the diaphragm through said means which amplifies such vibrations and delivers them to the diaphragm in their thus amplified condition.

A further feature of the invention resides in the mounting of the stylus bar for universal pivotal movement whereby the vibration of said stylus bar under the influence 45 of either lateral cut or hill and dale records is automatically provided for, said universal connection performing the further function of compensating for the movements of the amplifying means.

Features of the invention, other than those specified, will be apparent from the hereinafter detailed description taken in conjunction with the accompanying drawing.

In the accompanying drawing I have illustrated one practical form of the invention.

but the construction shown therein is to be understood as illustrative, only, and not as defining the limits of the invention.

Figure 1 is a plan view of a reproducer 60 embodying the present invention.

Fig. 2 is a side elevation thereof, and

Fig. 3 is a transverse section taken on line 3—3 of Fig. 1.

Referring to the drawing, A indicates any 65 well known or suitable form of sound box provided with the usual diaphragm B, which diaphragm is operated upon by a stylus bar for the purpose of translating the movements of the stylus into sounds cor- 70 responding to the undulations of a record.

C designates a stylus bar which, in accordance with the present invention, is preferably mounted for universal movement on a post d at one side of the sound box. Any 75 suitable form of universal connection may be employed, but, in that illustrated, the upper end of the post is rounded over and upon such end rests the stylus bar. Said bar is apertured to allow of the passage 80 therethrough of a bolt d', which extends through post d and is provided with a nut d'' at its lower end, for tightly binding the stylus bar between the upper end of the post and the head d''' of the bolt. Head d''' is in 85 the shape of a sphere or ball, and the upper surface of the stylus bar is provided with an arcuate seat d'''' of corresponding radius, so that ball d''' and seat d'''' form, in effect, a ball and socket joint. The hole through the 90 stylus bar is of greater diameter than bolt d' so that universal pivotal movement of the stylus bar is made possible. To pre- 95 clude a metallic sound due to the vibration of the stylus bar against adjacent metallic surfaces, cushioning washers d'''' are positioned at either side of the stylus bar, as shown in Fig. 3.

The upper end of the stylus bar is provided with the usual seat for a stylus C', 100 which is locked in place by the usual thumb screw.

In accordance with this invention, the diaphragm operating end of the stylus bar, instead of being secured directly to the diaphragm, as has heretofore been the case, co- 105 operates with certain amplifying means which receives the vibrations from said end of the stylus bar and transmits them in enlarged form to the diaphragm. In the specific form of the invention illustrated, this means embodies a disk E which is mounted,

2 by means of trunnions *e*, on a bifurcated supporting arm *e'* fixed to the sound box, as shown in Fig. 2, or in any other suitable way, so as to reach upwardly and over the face of the sound box and carry the disk *E* at its free end. Secured substantially at the circumference of said disk, and substantially tangential therewith, is a pin *f*, which is fixed at its opposite end to diaphragm *B*. Disk *E* is preferably pivoted to its supporting arm *e'* off center, so that the disk will be perfectly balanced and will not exert any pull or pressure on the diaphragm, but will allow the same to normally assume its neutral plane condition. The stylus bar extends from its pivot on the post *d*, and has its diaphragm operating end *c* fixedly secured to disk *E* as shown in Figs. 2 and 3, intermediate the outer circumference of said disk 20 and the axis on which it is pivoted.

It will thus be apparent that the radial distance between the axis of disk *E* and its point of attachment to the tangential pin *f* is greater than the radial distance between 25 said axis and the point of attachment between said disk and stylus bar. Accordingly, if the end *c* of the stylus bar is moved through a given arc, it will oscillate disk *E*, with the result that pin *f* will be longitudinally shifted through a greater arc because 30 of the difference in radial distance referred to. It will thus be apparent that the movements of the end *c* of the stylus bar, in their transmission through disk *E* to pin *f*, 35 will be greatly increased and will be imparted from the disk to the diaphragm in a greatly amplified condition over that in which they were received by the disk.

In order that the reproducer of this invention may be adapted to execute records of either the lateral or vertical cut type, the connection between the end *c* of the stylus bar and disk *E* is so positioned that a perpendicular extended from the diaphragm, 45 through the axis of oscillation of disk *E*, will not pass through said connection, nor will a line extending through said axis and parallel with the diaphragm intersect said connection. With such construction, the stylus bar will transmit an oscillatory movement to the disk, either when said bar is vibrating in a plane perpendicular to the diaphragm or in a plane parallel thereto, as there can be no point of dead centers either 50 in the perpendicular or parallel planes referred to. When the stylus bar is vibrating in perpendicular relation to the diaphragm, it will, manifestly, cause the disk to oscillate in synchronism with the vibrations, as will also be the case when said stylus bar is vibrating in substantially parallel relation to the diaphragm. In either instance, the universal pivotal mounting of the stylus bar allows of free movement of 55 said bar in either direction and precludes

binding between the different elements of the mechanism.

Thus, as the stylus travels over the record, said record imparts to the stylus bar vibrations, either perpendicular to the diaphragm 70 or substantially parallel thereto, in accordance with the type of record, be it either vertical or lateral cut, and said vibrations received at the end *c* of the stylus bar are transmitted on the lesser radius, through disk *E*, to the diaphragm through the greater radius, thereby increasing the amplitude of such vibrations. The diaphragm will thus be vibrated to a greater extent than it would if the diaphragm operating end of the stylus 80 bar were connected directly to the diaphragm, as has heretofore been the case.

In the foregoing description, I have set forth the invention in its preferred practical form, showing and describing the amplifying means as embodying a balanced disk. It will be understood, however, that, if desired, I may employ a lever connection which may be either balanced or not, and, moreover, while it is preferred to balance 90 the disk by pivoting it off center, as described, very good results may be obtained by pivoting it centrally so that it is not absolutely balanced. For these reasons, it is to be understood that the invention is not 95 restricted to the specific details shown and described, but that it is as broadly novel as is commensurate with the appended claims.

The device of the present invention has, moreover, been specifically described in its 100 embodiment in a reproducer. It will be manifest, from the foregoing description, however, that the principles involved may be availed of in recorder construction. In such construction, the principle of the unequal leverage due to unequal radii may be employed either in the specific manner shown in the drawing, or the connections may be reversed so that the distance between the axis of oscillation of the amplifying 110 member and the connection thereof with the stylus bar is of greater radius than the connection between the amplifying member and the diaphragm. This means merely a reversal in the connections so that the vibrations of the diaphragm will be enlarged in their transmission to the stylus bar (recording bar) of the recorder.

It will be manifest from the foregoing description that, when the vibrations are 120 transmitted from one vibrating part to the other, with increased magnitude, said latter part necessarily vibrates at a greater speed. Moreover, when the vibrations of one of the parts are transmitted to the other part, 125 with decreased magnitude, the part to which the vibrations are transmitted moves at a lesser speed.

When the structure of this invention is used as a reproducer, it may be readily at- 130

tached to either machine wherein the sound box is positioned edgewise with relation to the record, as in the Pathé machine, or in machines wherein the sound box is in side-
5 wise relation to the record, as is the case with the Victor machine.

Having thus fully described the invention, what I claim as new, and desire to secure by Letters Patent, is:

- 10 1. In a device of the class described, the combination of a sound box embodying a diaphragm, a mounting for a disk carried by said sound box, a disk pivotally mounted thereon, and a stylus bar pivotally mounted on a sound box, and secured at one end to the pivoted disk relatively close to the axis of said disk, and in operative connection between the diaphragm and the disk, said connection coöperating with the disk at a greater distance from its axis than the point whereat the stylus bar is associated with said disk, whereby the vibrations of the stylus bar are transmitted through the disk to the diaphragm in an amplified manner, said disk serving to steady the operations of the stylus bar.
- 15 2. In a device of the class described, the combination of a sound box embodying a diaphragm, a mounting for a disk carried by said sound box, a disk pivoted for oscillation thereon, a stylus bar mounted for universal pivotal movement on the sound box, and having one of its ends secured to the disk
- 20
- 25
- 30

exterior of the point of pivoting thereof, whereby the vibrations of the stylus bar, in planes either perpendicular to the diaphragm or parallel, result in the oscillation of the disk, and an operative connection between the disk and the diaphragm for the purpose of translating the oscillations of the disk into vibrations of the diaphragm.

3. In a device of the class described, the combination of a sound box embodying a diaphragm, a mounting for a disk carried by said sound box, a disk pivoted for oscillation thereon, a stylus bar mounted for universal pivotal movement on the sound box, and having one of its ends secured to the disk exterior of the point of pivoting thereof, whereby the vibrations of the stylus bar, in planes either perpendicular to the diaphragm or parallel, result in the oscillation of the disk, and an operative connection between the disk and the diaphragm for the purpose of translating the oscillations of the disk into vibrations of the diaphragm, the connections between the disk and the diaphragm coöperating with the disk at a greater distance from the axis thereof than the point at which the stylus bar is secured to said disk for the purpose of amplifying the vibrations of the stylus bar during their transmission to the diaphragm.

In testimony whereof I have signed my name to this specification.

CARL N. MOLLER.
